UNITED STATES PATENT OFFICE.

ANTON OHNEMUS, OF QUINCY, ILLINOIS, ASSIGNOR TO THE EXCELSIOR
STOVE AND MANUFACTURING COMPANY, OF SAME PLACE.

DESIGN FOR A STOVE.

SPECIFICATION forming part of Design No. 31,873, dated November 21, 1899.

Application filed October 26, 1899. Serial No. 734,888. Term of patent 7 years.

To all whom it may concern:

Be it known that I, ANTON OHNEMUS, a citizen of the United States, residing at Quincy, in the county of Adams and State of Illinois, 5 have invented and produced a new and original Design for a Stove, of which the following is a specification, reference being had to the accompanying drawing, forming part thereof.

The drawing is a perspective view showing 10 my design.

As shown in the drawing, the leading or material feature of my design consists of a cylindrical body A, the front of which is decorated with scroll-like figures, and a shield B. 15 Surmounting the body is a dome C, decorated with scrolls and above which is a scroll-dec-

orated pinnacle D. Beneath the body A is a cylindrical portion E, having vertical ribs, and above which is a scroll-decorated overhanging cap G. Beneath the portion E is a 20 base H, that surmounts legs I, both the base and the legs being decorated with scroll-like figures. Projecting from the base are shelves J.

I claim as my invention—

25 The design for a stove herein shown and described.

ANTON OHNEMUS.
